Primary Examiner — Deanna L Pratt*(74) Attorney, Agent, or Firm* — Brooks Kushman P.C.(57) CLAIM

The ornamental design for a picture holder, as shown and described.

DESCRIPTION

FIG. 1 is a perspective view of a picture holder according to one embodiment.

FIG. 2 is a perspective view of the picture holder FIG. 1 showing the flexible stem in an alternative configuration.

FIG. 3 is a front perspective view of the picture holder of FIG. 1.

FIG. 4 is a rear perspective view of the picture holder of FIG. 1.

FIG. 5 is a right-side perspective view of the picture holder of FIG. 1.

FIG. 6 is a left-side view of the picture holder of FIG. 1; and, FIG. 7 is a top perspective view of the picture holder of FIG. 1.

In FIGS. 1-7, the photograph held in the picture holder illustrates the environment of the claimed design and forms no part of the claimed design.

1 Claim, 4 Drawing Sheets(56)
